UNITED STATES PATENT OFFICE

166,049

CHAIR

Louis Elliott Rudin, Chicago, and Richard S. Schwartz, Glencoe, Ill., assignors to Spiegel, Inc., a corporation of Delaware

Application October 13, 1950, Serial No. 12,558

Term of patent 7 years

(Cl. D15—8)

To all whom it may concern:

Be it known that we, Louis Elliott Rudin and Richard S. Schwartz, citizens of the United States, residing, respectively, at Chicago and Glencoe, in the county of Cook and State of Illinois, have invented a new, original, and ornamental Design for Chair, of which the following is a specification, reference being had to the accompanying drawing, forming part thereof.

Figure 1 is a perspective view of a chair showing our new design, the chair being shown for use in the normal sitting position.

Fig. 2 is a similar view but showing the chair for use in a reclining position.

The side of the chair not shown is substantially the same in appearance as the side shown.

We claim:

The ornamental design for a chair, as shown and described.

LOUIS ELLIOTT RUDIN.
RICHARD S. SCHWARTZ.
